UNITED STATES PATENT OFFICE

BERNHARD E. ULVAD, OF LONG ISLAND CITY, NEW YORK, ASSIGNOR TO RUBY LAMP
MFG. CO. INC., OF NEW YORK, N. Y.

DESIGN FOR A LIGHTING FIXTURE ARM OR ARTICLE OF SIMILAR NATURE

Application filed February 10, 1930. Serial No. 34,468. Term of patent 3½ years.

To all whom it may concern:

Be it known that I, BERNHARD E. ULVAD, a subject of the King of Denmark, residing at Long Island City, in the county of Queens and State of New York, have invented a new, original, and ornamental Design for a Lighting Fixture Arm or Article of Similar Nature, of which the following is a specification, reference being had to the accompanying drawing, forming a part thereof.

Fig. 2 is a front elevational view of the same.

I claim:

The ornamental design for a lighting fixture arm or article of similar nature, as shown.

In testimony whereof I affix my signature.

BERNHARD E. ULVAD.
